E. R. WARNER,
COMBINED CLOTHESLINE SUPPORT AND REEL,
APPLICATION FILED DEC. 7, 1918.

1,373,279.

Patented Mar. 29, 1921.

UNITED STATES PATENT OFFICE.

EMERSON R. WARNER, OF BOWERSTON, OHIO.

COMBINED CLOTHESLINE SUPPORT AND REEL.

1,373,279.

Specification of Letters Patent. Patented Mar. 29, 1921.

Application filed December 7, 1918. Serial No. 265,709.

To all whom it may concern:

Be it known that I, EMERSON R. WARNER, a citizen of the United States, residing at Bowerston, in the county of Harrison and

5 State of Ohio, have invented new and useful Improvements in Combined Clothesline Supports and Reels, of which the following is a specification.

The present invention relates generally to 10 improvements in that class of inventions known as laundry, and more particularly has reference to a combined clothes line support and reel.

As the principal aim and object, the present invention contemplates the provision of 15 a device of the above mentioned character designed to partially support a plurality of clothes lines and at the same time is capable of inclosing the clothes lines when the latter are not in use in order that the lines may 20 be protected from the action of the weather.

It is an additional object of this invention to provide a device of the above character wherein means is employed for winding the 25 lines when not in use, while additional means acts in conjunction with the winding means for preventing accidental slipping of the lines when arranged in an extended clothes supporting position.

30 Among the other aims and objects of this invention, may be recited the provision of a device of the character mentioned wherein the parts are few, the construction simple, the cost of production low and the efficiency high.

Other improvements and novel details in 35 the construction and arrangement of the various parts of the apparatus will be brought out more in detail in the description 40 to follow, which for a clear understanding of the invention should be considered in connection with the accompanying drawings forming a part hereof, and wherein is disclosed for the purpose of illustration a convenient and satisfactory embodiment of the 45 invention. It is to be noted in this connection that minor changes in the construction and arrangement of parts may be made without departing from the principle of 50 operation of the various parts.

The invention is clearly illustrated in the accompanying drawings, in which:

Figure 1 is a front elevation of the device, 55 the casing being shown partly in section, and

Fig. 2 is a side elevation of the invention.

Similar characters of reference are employed in all of the above described views, to indicate corresponding parts.

Referring now, more particularly, to the accompanying drawings, there is provided, a base plate 1 from the under surface of which, spurs 2 project for assuring of the maintenance of the device in a stationary position when in use. Spaced standards 3 rise perpendicularly from the plate 1 and have their upper ends inclosed within and rigidly connected to a casing 4, while access is had to the casing through the instrumentality of a removable cover 5 for a purpose that will presently appear. Other standards 6 have their lower ends arranged within the casing and connected to the adjacent faces of the standards 3 by means of elongated bolts 7, nuts 8 being engaged on the bolts to prevent accidental movement of the standards 6. Still another standard 9 is now employed and has its lower end arranged between the upper ends of the spaced parallel standards 6 and rigidly connected thereto by means of elongated bolts 10 and nuts 11, which latter are removably engaged on the bolts.

Journaled longitudinally through the casing and transversely through the standards 3 and 6, which act as bearings, is a shaft 12, one end of which projects beyond one end of the casing and carries a crank handle 13. The portions 14 of the shaft between the ends of the casing and the adjacent standards 3 serve as a drum, while connected thereto, and windable thereabout, are clothes lines 15.

In order to support and guide the clothes lines, opposed eyes 16 are connected to the upper ends of the opposed standards 6, while other opposed eyes 17 are connected to the upper end of the standard 9; the main portions of the lines are trained through openings 18 in the top of the casing and respectively through the eyes 16 and 17. Rings 19 are connected to the outer ends of the lines, and are designed for removable engagement with hooks 20, which latter are adapted to be connected to a suitable support spaced from the standards and at a height about the same as the height of the eyes 17.

As intimated, improved means have been employed for preventing accidental unwind- 110 ing or slipping of the lines subsequent to extending them, and in reducing this feature

of the invention to practice, a ratchet wheel 21 is rigidly connected to the projecting end of the shaft 12 near the end of the casing, while coöperating with the teeth of the ratchet wheel is a pawl 22. This pawl is of the gravity operable type and is desirably pivoted by a pintle 23 to the end wall of the casing above the ratchet wheel.

- In use, the pawl 22 is held from engagement with the ratchet wheel to permit of the extending of the lines and the engagement of the rings 19 with the hooks 20. Subsequent to the extending of the lines and the placing of clothes thereon, the pawl is released whereupon the handle is engaged and rotated until the lines are sufficiently taut, being held in such position by the pawl which locks against one of the teeth of the ratchet wheel.
- It is believed in view of the foregoing description that a further detailed description of the operation of the invention is entirely unnecessary. Likewise it is believed that the advantages of the invention will be readily apparent. It is to be noted, however, that when the device is not in use, the handle may be rotated to draw the lines within the casing and wind them about the shaft in order to protect the lines from the action of the weather.

Having thus described my invention, what I claim is:

A device for the purpose indicated including a base plate having a pair of spurs on its under face adjacent the center, a pair 35 of spaced standards upstanding from the base plate, a second pair of spaced standards overlapping the upper ends of the first pair and disposed between the two and connected therewith, a third standard having its lower 40 end disposed between the two upper ends of the second said standards, a reeling device disposed adjacent the connecting ends of the first and second said standards, opposite eyes mounted respectively on the upper ends of 45 the second said standards, a second pair of opposed eyes mounted on the upper end of the third said standard, a pair of clothes lines connected with the reeling device and trained one through one of the eyes on each 50 of the second and third said standards, and means to preclude retrograde movement of the reeling device whereby the free ends of the two clothes lines may be anchored at remote points and tensioned to maintain the 55 set of standards in substantially vertical position.

In testimony whereof I affix my signature.

EMERSON R. WARNER.
